UNITED STATES PATENT OFFICE.

JOHN B. MCKENZIE, OF DELAFIELD, WISCONSIN.

GUARD OR PROTECTOR FOR TARGET-SHOOTING.

1,357,242.

Specification of Letters Patent. Patented Nov. 2, 1920.

Application filed February 21, 1920. Serial No. 360,538.

To all whom it may concern:

Be it known that I, JOHN B. MCKENZIE, a citizen of the United States, and resident of Delafield, in the county of Waukesha and 5 State of Wisconsin, have invented new and useful Improvements in Guards or Protectors for Target-Shooting, of which the following is a description, reference being had to the accompanying drawings, which are a 10 part of this specification.

The present invention relates to certain new and useful improvements in target shooting appliances, and refers more particularly to what may be termed a protector.

15 In target shooting, a beginner oftentimes shoots extremely wide of the target and consequently considerable damage is often done to surrounding territory due to such wide shooting. Hence, with this in mind, my invention has for one of its objects to provide 20 means for limiting the area surrounding the target which is visible to the shooter so that shots that are wide of the target will be stopped.

25 Another object of my invention is to provide means of the class described capable of ready transportation from place to place and so constructed as to permit the increase or decrease of the visible area surrounding 30 the target.

A further object of my invention is to provide a portable metal shell for the purpose described which will be comparatively light in weight to permit its transportation 35 from place to place with ease and facility, and which will provide efficient means for stopping shots that are wide of the target.

With the above and other objects in view which will appear as the description proceeds, my invention resides in the novel construction, combination and arrangement of 40 parts substantially as hereinafter described and more particularly defined by the appended claims, it being understood that such 45 changes in the precise embodiment of the herein disclosed invention may be made as come within the scope of the claims.

In the accompanying drawing I have 50 illustrated one complete example of the physical embodiment of my invention constructed according to the best mode I have so far devised for the practical application of the principles thereof, and in which:

Figure 1 is a diagrammatic view of my 55 improved protector illustrating its use.

Fig. 2 is a longitudinal sectional view taken on the line 2—2 of Fig. 3.

Fig. 3 is an elevational view looking at the end of my protector positioned nearest the shooter.

60

Fig. 4 is a top plan view thereof, and

Fig. 5 is a fragmentary perspective view illustrating the manner of pivotally securing the upper end of the adjustable plate closing the end of the protector nearest the 65 target to the protector shell.

Referring now more particularly to the accompanying drawing, my protector consists broadly of a portable metallic shell 10 comprising a frame formed of channel and 70 angle iron members 11 secured together to provide the desired shape and having side metal plates 12 and a top metal plate 13 riveted or otherwise secured thereto to provide an open ended protector.

75 The forward lower end of the frame members 11 are connected together by a transverse axle 14 having its ends extended beyond the sides of the shell for receiving supporting wheels 15, and the lower rear ends 80 of the frame are connected by an axle 16 also having its ends projected beyond the sides of the shell to receive rear supporting wheels 17. The rear axle 16 has its intermediate portion depressed as depicted in Figs. 2 and 85 3 to be out of the line of sight of the shooter, as will be obvious.

The forward end of the shell is closed by a metal plate 18 having hook or eye members 19 secured to its upper end and pivotally engaging a rod 20 connecting the upper forward ends of the frame to pivotally mount the plate. The plate 18 is provided with an aperture 20' and has a substantially cylindrical guard 21 secured thereto in alignment with the aperture.

90 The lower end of the plate 18 engages with two projections 22 carried by the lowermost frame members 11 and is adapted to be selectively engaged in notches or recesses 23 95 formed therein for maintaining the lower end of said plate in various positions with respect to the shell proper. As best shown in Figs. 3 and 4, the rear end of the shell is of less area than the forward end, as bullets 100 striking the plate 18 will be deflected to one side and by reason of the decreased area of the rear end, will be prevented from injuring the shooter positioned near by.

105 In use, the protector is interposed between 110

the target 24 and the shooter designated as at 25, with its rear end nearest the shooter and its forward end carrying the plate 18 nearest the target. The shell is so spaced from the 5 shooter as to permit the desired area surrounding the target to be visible to the shooter, and the target is fired at through the opening 20'.

In the event that the shooter fails to take 10 proper aim, if the shot is wide of the visible area, the same will either hit the plate 18 and be stopped and deflected toward the ground or else if the same hits the edge of the plate surrounding the opening 20' the 15 same will be deflected to one side against the guard 21, and thence to the ground.

The visible area is adjusted, as before stated, by varying the distance between the shooter and the protector and the elevation 20 of the target is governed by engaging the lower end of the plate 18 in notches 23.

Besides providing an efficient protector for the territory surrounding the target, my device also provides means for saving the 5 lead from the wasted bullets which are deflected or stopped by the protector as will be readily apparent to those skilled in the art to which an invention of this character appertains.

30. What I claim as my invention is:

1. The combination with a target, of means interposed between the target and the shooter and distant from the latter for limiting the area surrounding the target which 35 is visible to the shooter and comprising a metal shell having its end adjacent the shooter open and its opposite end apertured to provide a sight of the target.

2. The combination with a target, of 40 means interposed between the target and the shooter and distant from the latter for limiting the area surrounding the target which is visible to the shooter and comprising a metal shell having its end nearest the shooter 45 open and its end nearest the target apertured, and a guard surrounding the aperture whereby bullets striking the edge of the shell surrounding the aperture will be prevented from being deflected to one side.

50. 3. The combination with a target, of means interposed between the target and the shooter and distant from the latter for limiting the area surrounding the target which is visible to the shooter and comprising a 55 metal shell having its ends nearest the shooter and the target open, an apertured

plate closing the end nearest the target, and a substantially cylindrical guard secured to the outer face of said plate in line with the aperture therein.

4. The combination with a target, of means interposed between the target and the shooter for limiting the area surrounding the target which is visible to the shooter and comprising a metal shell having its ends 60 nearest the shooter and the target open, an apertured plate closing the end nearest the target and having one end pivotally secured to the shell and its other end free, and means for varying the position of the free end of 65 said plate with respect to the shell to adjust the vision of the shooter.

5. The combination with a target, of means interposed between the target and the shooter and distant from the latter for limiting 70 the area surrounding the target which is visible to the shooter and comprising a wheeled metal shell having its end nearest the shooter open and its end nearest the target apertured.

6. The combination with a target, of means interposed between the target and the shooter for limiting the area surrounding the target which is visible to the shooter and comprising a wheeled metal shell having its 75 ends nearest the shooter and the target open, an apertured plate closing the end of the shell nearest the target and having its upper end pivotally secured to the shell, and means engageable with the plate to maintain its lower end in a desired position with respect to the shell to govern the elevation of the area surrounding the target which is visible 80 to the shooter.

7. The combination with a target, of 85 means interposed between the target and the shooter for limiting the area surrounding the target which is visible to the shooter and comprising a wheeled metal shell having its 90 ends nearest the shooter and the target open, an apertured plate closing the end of the shell nearest the target and having its upper end pivotally secured to the shell, and means engageable with the plate to maintain its lower end in a desired position with respect 95 to the shell to govern the elevation of the area surrounding the target which is visible to the shooter, the visible area being governed by the relative positions of the shooter and the shell.

In testimony whereof, I affix my signature.
JOHN B. MCKENZIE.
